SIGN HOLDING DEVICE

Henry C. Pfaff, Jr., East Orange, N. J.

Application June 15, 1937, Serial No. 148,263

2 Claims. (Cl. 40—145)

This invention relates to improvements in street sign display devices and more particularly to devices of the type described in U. S. Letters Patent 1,968,219 issued to me on July 5 21, 1934.

In the sign holding device of my said patent, a frame member is employed comprising a pair of substantially U-shaped internally channelled sections, each section having at the free ends of 10 the legs thereof semi-cylindrical bosses, so that when the sections are assembled together said semi-cylindrical bosses cooperate to form cylindrical bosses, and clamping means surrounding said bosses to hold the sections together.

These frame members are used to support metal sign plates which are generally covered with baked or porcelain enamel, and while the frame disclosed in my said patent constitutes a considerable advance in the art, my present invention comprises a further important improvement thereon.

In making the frame disclosed in my patent a gasket of fiber or lead is ordinarily provided within the frame channel to assist in holding the 25 sign plates in position. In the casting of the frame warpage frequently occurs and misalignment of the legs of the frames frequently occurs during the cooling of the casting.

It is an object of my invention to provide a 30 frame of the character described which is provided with means for guiding the sign plates and for holding them in spaced position within the channels of the frame without the use of a gasket.

A further object of my invention is to provide 35 a sign holding device of inherently stable construction so designed as to prevent warpage in the casting of the frames and to prevent the misalignment of the legs of the frames during the operation of casting.

A further object of my invention is to provide 40 a frame of the character described so designed as to facilitate the assembly of the sign device.

A further object of my invention is to provide 45 the frame with means to prevent the distortion of the frame during the assembly of the sign device, thereby obviating the danger.

These and other advantageous objects which 50 will later appear, are accomplished by the simple and practical construction and arrangement of parts hereinafter described and exhibited in the accompanying drawing, forming part hereof, and in which:

Fig. 1 is an elevational view of the device when used to indicate two intersecting streets, parts 55 being broken away for the sake of clarity,

Fig. 2 is a perspective view of the two part sign plate holding frame, embodying my invention,

Fig. 3 is a sectional view taken on line 3—3 of Fig. 1, and

Fig. 4 is a sectional view taken on line 4—4 of Fig. 2, in the direction indicated by the arrow.

Referring to the drawing, in Fig. 1 is shown a sign plate holding frame, comprising two U-shaped parts 6, 7 identical in size and shape so 10 that they can be readily interchanged. Each part has an internal channel 8 to receive and support a sign plate 9 which are generally covered with baked or porcelain enamel. Adjacent the free ends of the legs of the parts 6 and 7 and 15 connecting the internal channels 8 thereof is a connecting brace or strip 10 which may be of any desired configuration, being preferably, as shown in Fig. 2, of rectangular cross section and of such dimensions that, as shown in dotted lines, 20 in Fig. 4, the sign plates 9 may be positioned on each side of the connecting strip 10 within the channel 8.

The width of the channel 8 of the frame parts is greater than the width of the plates 9 to be 25 positioned therein, so that by making the connecting strip 10 of a predetermined width the said plates may be snugly but firmly secured within the channel, thus providing only sufficient space to provide a sliding fit for the plates 9. 30 The necessity for a gasket, required heretofore, is thereby eliminated.

I have found, in practice, that the frame parts 6 and 7 may be cast with the connecting strip 10 forming an integral part of the casing; this 35 construction provides the parts 6 and 7 with inherent stability and practically eliminates any danger of the distortion of said parts during the cooling of the casting. The danger of misalignment of the ends of the parts is also obviated. 40 The connecting strip 10 further prevents the free ends of the parts 6 and 7 from being compressed inwardly with the resultant danger of breaking and chipping the plates 9 therein.

The sign holding device of the character described herein is used to designate street intersections and the like and is subjected to inclement weather and climatic conditions. The construction described herein has been found to provide an aligned, rugged frame which will not 50 become distorted in use. The construction described also precludes the danger of excessive expansion and contraction of the frame due to climatic conditions.

Each of the parts 6 and 7 is substantially U- 55

shaped and has on opposite sides semi-cylindrical bosses 11 and 12 so that when the frame is assembled, the bosses fit together to provide cylindrical bosses as shown in Figs. 1 and 3. An external rib 13 preferably triangular in cross section, as shown in Fig. 2 extends around the periphery of the frame.

Passing through the bosses 11 and 12 is a rod 14, (see Fig. 3) which is preferably provided with a cap 15 integral therewith or threadedly secured thereto, said cap having opposing triangular grooves 16 adapted to fit over the rib 13 of the frame, the internal diameter of the cap 15 being greater than the diameter of the cylindrical boss formed by the bosses 11 and 12. The cap is usually provided with an integral ornament 17.

When for example two sign plates are used to designate two intersecting streets the top rib 13 of the upper frame is engaged by the cap 15, while the bottom rib on the upper frame is engaged by opposing triangular grooves 18 in a collar 19 which surrounds the bosses on the lower side of the upper frame and on the upper side of the lower frame, (see Fig. 1), the collar 19 having grooves 18 to also engage the upper rib of the lower frame. The lower rib 13 on the lower frame fits in grooves 21 in a collar 22 integral with a two-part cap 23 which fits over the top of and is clamped by suitable means to a cylindrical supporting post 24. The lower end of the rod 14 is preferably threaded and passes through an aperture in cap 23.

In assembling the device, cap 15 is fitted over the bosses 11 of the upper frame, the rod 14 passing through the bosses 11 and between the sign plates 8 which are bowed or spaced at the center by the strips 10 to receive the rod 14, and the collar 19 is then slipped over the rod 14 and into position over the bosses on the underside of the upper frame; the lower frame members are then placed in position with the upper bosses 11 thereon surrounded by collar 19.

The cap 23 is then positioned over the lower bosses 12 of the lower frame after which a nut 25 is threaded on the end 26 of the rod 14 and rotated to draw the parts firmly together. Up-

ward movement of the nut 25 is prevented by cap 23 so that rotation of the nut 25 draws the rod 14 downward to clamp the parts together.

The cap 23 is then clamped on to the supporting post 24. Obviously when the device is used for a sign frame it is not necessary to use the collar 19.

The collar 19 is provided with a plurality of grooves 20 to enable the sign frames to be arranged at various angles to each other.

From the above description it will be seen that I have provided a sign holding device of simple structure requiring no nuts or bolts, and which can be readily assembled by a single unskilled workman. The parts are fitted together so that allowance can be made for limited expansion and contraction due to changing weather.

The foregoing disclosure is to be regarded as descriptive and illustrative only, and not as restrictive or limitative of the invention, of which obviously embodiments may be constructed, including many modifications, without departing from the general scope herein indicated and denoted in the appended claims.

Having thus described my invention, what I claim as new and desire to secure by Letters Patent, is:

1. In a sign holding device, a frame member comprising a pair of substantially U-shaped internally channelled sections, each section having bosses at the free ends of the legs thereof, means surrounding said bosses to hold the sections together, and members connecting the legs of each section adjacent the bosses, said members being positioned on the longitudinal center lines of said sections.

2. In a sign holding device, a frame member comprising a pair of substantially U-shaped internally channelled sections, each section having bosses at the free ends of the legs thereof, cylindrical collars surrounding said bosses to hold sections together, and members connecting the legs of each section adjacent the free ends thereof, said members being positioned on the longitudinal center lines of said sections.

HENRY C. PFAFF, JR.
